UNITED STATES PATENT OFFICE.

NICHOLAS PHILLIPP DI CESARE, OF SHEBOYGAN, WISCONSIN, ASSIGNOR TO KOHLER COMPANY, OF KOHLER, WISCONSIN, A CORPORATION OF WISCONSIN.

ELECTROPLATING RACK.

Application filed August 22, 1927. Serial No. 214,659.

This invention has for its object to provide a rack for use in the chromium plating of such hollow screw-threaded articles as the drain connections for sinks and the like.

5 Another object of the invention is to provide a rack into which the articles to be plated may be threaded for support and for electrical connection in suitable supporting rings arranged in rows one above the other, and in 10 which each rack is provided with anodes extending through the supporting rings and the articles mounted thereon, there being a series of such rows of supporting rings one above the other adapting the rack for use with a 15 deep bath for quantity production.

Another object of the invention is to provide such racks constituting complete units adapted to be moved from place to place with the articles secured thereto and capable of 20 having the anodes and anode frames readily replaced.

With the above and other objects in view the invention consists in the rack for chromium plating as herein claimed and all 25 equivalents.

Referring to the accompanying drawings in which like characters of reference indicate the same parts in different views,

Fig. 1 is a front view of an electro-plating 30 rack constructed in accordance with this invention;

Fig. 2 is a side view thereof with parts sectioned;

Fig. 3 is a plan view thereof; and

35 Fig. 4 is a sectional view of a fragment of a supporting ring.

In these drawings 10 indicates a pair of vertical side rods connected at intervals by horizontal cross rods 11 somewhat in the manner of the rungs of a ladder. These cross rods 11 are preferably welded to the side rods and are made up of shouldered threaded rings 12 welded to short rod sections, said rings being regularly spaced apart and occupying 40 a horizontal plane. The side rods and the cross rods together form a cathode frame for supporting the articles to be electro-plated and for establishing electrical connection therewith, such articles, in this instance drain outlets 13 for sinks and the like, being threaded in the rings 12 against the shoulders. The upper ends of the side rods 10 may terminate in hooks 14 for a supporting connection and current carrying connection with 45 the usual negative terminal bars, not shown,

of the electro-plating vat, and projecting from these hooks are rods 15 forming handles by means of which the rack may be lifted and moved from place to place.

Removably secured to the cathode frame 60 and insulated therefrom is an anode frame comprising vertical rods 16 detachably connected at their upper ends with a metal top rod 18 and at their lower ends with a bottom rod 19 of insulating material. The rods 16 65 form removable anode carriers, the anodes 17 in the form of hooks being detachably secured thereto and each extending upwardly through one of the rings 12 and the article 13 mounted thereon. The top rod 18 has its 70 ends bent toward the cathode frame and connected by blocks 20 of insulating material with angle pieces 21 detachably secured to the side rods 10 of the cathode frame, while at the bottom, rods 16 have their ends bent 75 toward the cathode frame and then downwardly and detachably connected to the insulating bottom rod 19, which is removably secured at its ends to the lower ends of the side rods 10.

80 The detachable connections between the side rods 10 and the angle pieces 21 of the top rod and between the side rods 10 and the bottom rod 12 are preferably in the form of screws threading into said side rods to permit the 85 anode frame to be readily detached from the cathode frame, and the detachable connection between each anode 17 and the anode carrier 16 preferably consists of screws passing through upturned ends of the anodes and 90 threading into the anode carriers. It will be noted that while the anodes 17 attached to the vertical portion of the anode carrier 16 are substantially U-shaped, those in the lower row connected with the horizontal portion are 95 substantially L-shaped.

At its back, the top rod 18 is provided with an arched clip 22 carrying an angular terminal projection 23 for convenient clamping engagement with the positive terminal of the 100 generator or other source of electric current supply.

With this invention the articles to be plated, such as the drain connectors 13 for sinks and the like, are threaded in the rings 105 12 into firm contact with the shoulders of the rings and when so positioned have the anodes centrally positioned within them, so that the rack may be lowered into the bath and the connections made for the plating operation. 110

The articles being arranged in vertical rows are suitable for use in deep baths and co-operate with each other in producing an efficient circulation of the electrolyte, each article having a firm mechanical support as well as a firm electrical connection with the cathode frame. When it is necessary to replace anodes, the anode frame may be detached from the cathode frame and replaced with another 10 without a material loss of time and the individual anodes may be disconnected from the anode frame and replaced with others to restore the anode frame to condition for further use. Thus the anode frame and the cathode 15 frame are separate complete units capable of being joined into an integral portable structure.

The present invention is particularly designed for chromium plating with which it is 20 found of great importance in order to obtain the proper plating of the interior of the tubular drain outlets to have the anode pass centrally therethrough, but it is to be understood that the invention is not limited to such purpose but is capable of use for electro-plating 25 of hollow articles generally.

What I claim as new and desire to secure by Letters Patent is:

1. An electro-plating rack comprising a 30 cathode frame, an anode frame detachably connected therewith, said cathode frame including horizontal cross rods one above the other and each cross rod containing a row of supporting rings, and said anode frame including vertical anode carriers, each with a 35 vertical row of hook-shaped anodes extending through the supporting rings.

2. An electro-plating rack comprising a 40 cathode frame consisting of vertical side rods connected by horizontal cross rods at intervals forming a ladder-like construction, each of the cross rods containing a row of supporting rings; and an anode frame detachably 45 connected with the cathode frame and comprising vertical anode carriers, top and bot-

tom rods connected therewith and having detachable insulating connection with the side rods of the cathode frame, and hook-shaped anodes on the anode carriers projecting through the rings.

3. An electro-plating rack for hollow screw-threaded articles, comprising a cathode frame consisting of vertical side rods connected at intervals by cross rods containing rows of screw-threaded supporting rings to 55 have the articles threaded therein; and an anode frame consisting of vertical anode carriers, top and bottom rods connecting the ends of the anode carriers and having detachable insulating connection with the side rods of the cathode frame, and hook-shaped 60 anodes detachably mounted on the anode carriers and passing through the supporting rings.

4. An electro-plating rack for hollow screw-threaded articles, comprising a cathode frame consisting of vertical side rods and horizontal rods connecting the side rods at intervals and each containing a row of shoudered screw-threaded supporting rings to 65 have the articles threaded therein in contact with the shoulders, hooks at the upper ends of the side rods for supporting the rack and for making electrical connections therfor, and handles on the hooks; and an anode frame 70 consisting of vertical anode carriers, top and bottom rods connecting the ends of the anode carriers, insulating blocks connected to the ends of the top rod, angle pieces on the insulating blocks having detachable connection 75 with the side rods of the cathode frame, the bottom rod being of insulating material and having detachable connection with the side rods of the cathode frame, hook-shaped anodes 80 detachably mounted on the anode carriers and projecting through the supporting rings, and a terminal connector on the top rod.

In testimony whereof, I affix my signature.
NICHOLAS PHILLIPP DI CESARE.
